UNITED STATES PATENT OFFICE

ELMER V. KLINE, OF UNIVERSITY CITY, MISSOURI, ASSIGNOR TO VICTOR PHARMACAL COMPANY, INC., OF ST. LOUIS, MISSOURI, A CORPORATION OF MISSOURI

SAFETY RAZOR BLADE SHARPENER

Application filed July 11, 1931. Serial No. 550,087.

This invention relates to a device for use as a safety razor blade sharpener.

An object of the invention is to provide a device designed and adapted for use as a safety razor blade sharpener and including, essentially, a body of sufficient width or length to function as a handle whereby the body may be conveniently supported and held in one hand or may be laid with one side upon a support and held stationary by one hand, and having a curved wall against which a safety razor blade may be pressed and bent and operated in order to sharpen the opposite edges of the blade, and also having a portion adapted to be engaged by the thumb of the hand that manipulates the razor blade in order to steady and prevent the hand from slipping and to enable the operator to manipulate the razor blade along and against the curved wall with approximately a uniform and desired pressure.

Other objects of the invention will be made apparent by the following description, reference being made to the annexed drawing, in which—

Fig. 1 is a perspective view of one form of my improved safety razor blade sharpener.

Fig. 2 is a vertical sectional view showing clearly the construction and arrangement of the curved wall by and against which the razor blade is sharpened, and also showing the construction engaged by the thumb of the hand that manipulates the blade in order to enable the operator to control the manipulation of the blade more effectively.

Fig. 3 is a perspective view of the device clearly showing the relationship of the thumb engaging portion with respect to the curved wall.

In the embodiment of the invention shown, my improved safety razor blade sharpener comprises a body formed with an end 1, a wall 2 opposite from the end 1, a pair of side walls 3 and 4 integrally connecting the end 1 with the end wall 2, a side wall 5 having its ends integrally connected with the end 1 and the end wall 2, respectively, and its side edges merging to integral connection with the walls 3 and 4, respectively. The wall 6 that is opposite from the wall 5 is curved

toward the wall 5 on a uniform radius of curvature, and has its upper and lower ends integrally united with the upper end 1 and the lower wall 2, respectively, and its side edges integrally united and merging with the walls 3 and 4, respectively. Thus, the body is substantially rectangular with the exception of the curved wall 6 against and along which a safety razor blade is curved and bent along lines parallel with the longitudinal axis and with the side edges of said blade on approximately the same radius of curvature as the radius of curvature of the wall 6. Oscillation and manipulation of the razor blade thus held against the wall 6 will sharpen the opposite side edges of the blade because the surface of the said wall 6 is constructed and designed for that purpose.

The entire body of the device may be made of glass. If desired, the body may be hollow so as to provide a container for any desired substance.

The end wall 2 is formed with a central concaved portion 7, thus producing on the outer side of said wall 2 a concavity 8 constructed and arranged to receive comfortably the ball of the thumb of that hand of the operator used to bend and manipulate the razor blade against and along the wall 6. Thus, the concavity 8 will prevent the thumb from slipping and will also function as a rest for the thumb so that the operator may apply approximately uniform and continuous pressure against the razor blade and thereby press the razor blade with approximately uniform and continuous pressure against the wall 6. The concavity 8 also functions as a fulcrum or pivot for the thumb so as to facilitate the manipulation of the fingers engaging the razor blade. The device 8 is a genuine convenience in this regard, as it performs satisfactorily the several functions indicated, irrespective of whether the device is supported in the hand or is placed upon a support when being used as a sharpener.

The walls 3 are of sufficient width to constitute a handle whereby the device may be conveniently supported in one hand, and the construction opposite the curved wall 6 is

such that the device may be easily laid upon a support and may be held substantially stationary on said support without possibility of rocking or oscillating while the razor blade 3 is being manipulated and sharpened. The walls 3 and 4 are of sufficient width to permit the device to be held on a support in the manner stated without danger of cutting the fingers of the hand holding the device while 10 the razor blade is being sharpened.

As indicated, the device may be made in the form of a container. In such case, the end 1 is formed with an opening 9 surrounded by a projecting neck 10 through which the 15 contents of the container may be discharged. The neck 10 may be closed by any suitable closure, as by a cap 11 screwed into engagement with a thread 12 on the outer side of the neck 10.

20 It is now clear that my invention may be manufactured inexpensively and is a genuine convenience for use in sharpening safety razor blades. The device may be held and manipulated more conveniently than any device 25 for this purpose with which I am familiar, and these advantages are obtained as a result of the novel construction shown and described.

I claim:—

30 1. A safety razor blade sharpener comprising a body of generally rectangular shape having one flat wall and the opposite wall curving on uniform radius of curvature from said flat wall and having in one end wall 35 a concavity arranged to receive and substantially fit the ball of the thumb of the operator when the operator presses and manipulates a safety razor blade against said curved wall, and an engageable projection in connection with the end of said body opposite from 40 said concavity.

2. A safety razor blade sharpener comprising a body having a curved wall along one side thereof bowing inwardly toward the opposite wall and having side walls constituting 45 a handle for holding and supporting said body and having in one end wall a cavity arranged to receive and retain the thumb of that hand used by the operator to press and 50 manipulate a safety razor blade against said curved wall.
